BABY PACIFIER

Milton A. Moffat, 3437 Via La Selva,
Palos Verdes Estates, Calif.

Filed Aug. 3, 1961, Ser. No. 66,235

Term of patent 3½ years

(Cl. D83—8)

FIGURE 2 is a side elevational view thereof, it being understood that both sides are identical in appearance;

I claim:

The ornamental design for a baby pacifier as shown and described.
